UNITED STATES PATENT OFFICE.

CLARENCE YUNCKER, OF DODGE CITY, KANSAS.

RACK FOR COOKIE-BOXES.

Specification of Letters Patent.

Patented Nov. 9, 1920.

1,358,406.

Application filed August 7, 1919. Serial No. 315,891.

To all whom it may concern:

Be it known that I, CLARENCE YUNCKER, a citizen of the United States, residing at Dodge City, in the county of Ford and State of Kansas, have invented certain new and useful Improvements in Racks for Cookie-Boxes, of which the following is a specification.

This invention relates to store furniture, and more especially to display racks; and the object of the same is to produce a rack of this kind for holding boxes containing cookies and the like in such position that their tops will be displayed and may be opened.

The invention consists primarily in the construction of the rack itself so that the top of the boxes are presented obliquely to the front, and it consists secondarily in providing means within the rack for fastening the boxes therein so that they will not become displaced when their lids are raised, but may be removed entirely when they are to be replaced by others.

25 The invention further contemplates the provision of a specific form of box holder for carrying out the idea above mentioned.

A still further object is to generally improve racks of this kind.

30 In the accompanying drawings—

Figure 1 is a general perspective view of this improved rack with a number of boxes therein.

Fig. 2 is an enlarged cross section through 35 one shelf of the rack, showing a box in elevation thereon and with its lid or cover closed in full lines and raised in dotted lines.

Fig. 3 is a perspective detail of the box 40 fastener.

The rack comprises spaced uprights or end standards 5 connected by a top 6 which may well be flat, and also connected by a series of shelves whereof each is shown herein as made up of a rear strip or board 7 inclined downwardly and forwardly and a front strip or board 8 inclined downwardly and rearwardly and preferably spaced at its lower edge from the lower edge of the 45 rear strip as seen at 9 in Fig. 2. This produces a trough-like shelf whereon rectangular and substantially cubical boxes 10 may be supported as indicated. The lid or cover 11 of each box is hinged to a metal reinforcing frame 11' as at 12 and may be raised 50 as seen in dotted lines in Fig. 2, without

interfering with the front board 8 of the shelf above. Said lid is by preference stamped or formed with panels such as 13 and 14 which may contain advertising matter, either painted thereon or displayed by means of a card or label, under glass or not and removable or otherwise at will; and it is quite possible that one of the panels may be simply a sheet of glass through which the prospective customer can see the contents of the box when the lid is closed. The frame 11' of each box is provided on both sides and preferably near the forward upper corner of the box with hooks 15, and if the body 70 of the box is of metal, these hooks may well be riveted or soldered thereto.

The box fastener whose details are best seen in Fig. 3 comprises a bearing secured to the rear board 7 and shown herein as a single sheet of metal 20 bent at its center into an elongated eye or tube 21, the sheet being attached to the back of the board 7 by appropriate means 22 such as screws passing through holes 23 in both leaves of the bearing. Within the element 21, if it be a single elongated eye as shown, is pivotally mounted the center of a substantially U-shaped wire member or bail whose arms are herein numbered 24, but it will be seen 85 from what follows that these arms might be independently pivoted in the bearing and the latter might in fact have independent eyes instead of a single long eye as shown. Each arm is bent at 25 so as to pass over the upper edge of the rear board 7, is then carried forward and given a slight depression 26, and its front end is bent downward obliquely into a handle 27. A contractile spring 28 is connected at its upper end with 90 said depression and at its lower end with a similar depression 26' at the center of a short rod 29 which passes through both boards 7 and 8 as seen in Fig. 2. If a single U-shaped member is used, the two arms 100 will stand parallel and will be spaced a sufficient distance to permit a box to be inserted between them, but whether the arms are connected with each other or not, the springs 28 draw their forward ends normally downward and will hold them engaged with the hooks 15 as seen in Fig. 2.

For preventing the accidental movement of the box upon the trough-like shelf, one or more spurs 30 may be passed upward 110 through one of the boards as seen in Fig. 2, and its point will indent or perhaps punc-

ture the wall or bottom of the box when the latter is put into the rack. After the box has been emptied or when it becomes worn or disfigured and it is desired to remove it, 5 the two handles 27 are grasped and raised so that the two arms 24 are lifted off the hooks 15, the springs 28 stretching to permit lifting movement of said arms. The arms are then swung outward away from 10 the box, and the box itself is grasped and lifted off the spur or spurs 30 and removed bodily from the rack—being replaced by a new one then or later. It is obvious that boxes containing cookies, candies, biscuits, 15 and the like may be displayed on a rack of this kind with advantage, the shape of each shelf holding the tops of the boxes presented directly to the prospective customer, and a box fastener being obviously provided 20 for preventing the accidental displacement of the box from the rack. This, of course, might be the result of accident, mischievousness on the part of waiting customers, vibration or jar which would follow the moving 25 of the rack from place to place, or the bumping against it of other pieces of store furniture which is unavoidable in crowded places.

Having thus described the invention, what 30 is claimed as new is:

1. A display rack for boxes comprising spaced uprights, a shelf connecting the uprights and composed of a rear board inclined downward and forward and a front 35 board inclined downward and rearward, the lower edges of said boards being spaced from each other, and means for yieldably holding rectangular boxes in the angle formed by the upper faces of said boards 40 with the adjacent corners of the boxes extending within the space between the lower edges of said boards.

2. In a display rack for boxes, the combination with a frame including end up- 45 rights and a transverse trough-like shelf connecting them; of hooks on the sides of

the boxes which are supported on said shelves, and for each box a pair of spring-actuated arms connected with the shelf and adapted to removably engage said hooks for yieldably holding the boxes in the angle formed by the trough-like shelf.

3. A display rack having a trough-shape supporting shelf; a box having a hook, spur projecting inwardly from the shelf and adapted to pierce the box, and a spring-pressed arm mounted on the shelf and removably engaging said hook for holding the box in the angle of the trough of the shelf and against the bill of the spur.

4. A display rack having a trough-shaped supporting shelf, a box having hooks secured to the opposite side walls thereof, arms pivoted to the shelf and having their free ends removably engaging said hooks, and a spring bearing the arms in a direction to press the box within the trough of the shelf.

5. A display rack having a trough-shaped supporting shelf, a box having a hook, an arm pivoted at one end to the shelf, having an indentation at its mid-length and provided with a downturned front end removably engaging said hook, and a spring fastened at one end to the supporting shelf and having its other end engaging said indentation, the spring moving the arm normally in a direction to hold the box within the trough of the shelf.

6. In a display rack, the combination with a box having outwardly projecting members on its sides; of a V-shaped shelf in which the box is supported, a bearing on the rear board of the shelf, a U-shaped element having its center pivoted in said bearing and its arms passing alongside the box and detachably engaging said members thereon, rods across the angle of the shelf, and springs connecting the rods and arms in pairs, for yieldably holding the box within the V of the shelf. 85

In testimony whereof I affix my signature.
CLARENCE YUNCKER. [L. S.] 90
